(57) **CLAIM**

The ornamental design for a traveling working machine, as shown and described.

DESCRIPTION

FIG. 1 is a front elevational view of the traveling working machine;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a top, rear and left side perspective view thereof.

The phantom lines shown form no part of the claimed invention.
